FLUID ACTUATED HEAD FOR ABRADING ELEMENTS

Harry M. Whittaker, Detroit, Mich., assignor to
 Micromatic Hone Corporation, Detroit, Mich.,
 a corporation of Michigan

Application August 13, 1937, Serial No. 158,967

3 Claims. (Cl. 51—184.3)

My invention relates to abrading devices and particularly to a method and means for actuating the abrading elements of a honing tool.

Heretofore it has been the common practice to employ one or more conical elements which are movable axially of the tool as a unit or toward and away from each other for the purpose of adjusting abrading elements radially of the axis of the tool body. Various schemes have been employed to provide flexibility to the abrading elements permitting them to tilt independently of the other relative to the tool axis, and to float as a unit relative thereto. Difficulty, however, has always been experienced in view of the fact that the hardness of the abrading elements or stones is non-uniform so that certain abrading elements will wear away faster than others, loading certain of the elements beyond an intended amount causing the break-down and the more rapid wearing of the elements. This also has a detrimental action on the machining operation occurring on the cylinder wall and the high polish desired is difficult to obtain.

In practicing my present invention, I utilize actuating means for the elements which, while operating under the same pressure, are movable independently of each other. The abrading elements are urged outwardly under like pressure, the same or different amounts, depending upon the dissimilarity in wear of the elements. Thus if one or more of the abrading elements have worn away faster than the other, this will not cause an overloading condition, since, irrespective of the wear, the same pressure will be provided between the surfaces of the abrading elements and the cylinder wall. The mechanism is so constructed as to permit the feeding of one of the elements a greater amount than the other. The stone which has been worn away a greater amount is fed further outwardly than the other stone or stones and as the stone continues to wear away faster than the others, will be fed outwardly more rapidly. All of the stones will thereby be forced against the cylinder wall with like pressure at all times.

I have illustrated the abrading element as being in part similar to a honing device illustrated in the copending application of K. W. Connor, Serial No. 76,519, filed April 27, 1936, now Patent No. 2,108,029, dated February 8, 1938, and that to Harris, Serial No. 116,774, filed December 19, 1936, now Patent No. 2,252,176, dated August 12, 1941, both of which have been assigned to the assignee of the present invention. The application of my principle to this device is, how-

ever, employed for the purpose of illustration, and is not to be considered as being limited to this particular construction, as it will be understood by anyone skilled in the art that the principle herein illustrated and to be described will apply to other types of abrading devices, either to an entire abrading machine or to an independent tool.

Accordingly, the main objects of my invention are: to provide individually movable abrading elements for a honing tool; to apply like pressure to abrading elements to independently move them radially of the axis of the honing tool; to provide a fluid pressure which operates independently for urging the abrading elements independently radially of a honing tool; to employ a plurality of pistons operated by a common source of fluid pressure for actuating abrading elements radially independently of each other; and in general to provide a method and means for honing cylinder walls wherein the abrading elements are actuated independently under like pressure, which is simple in construction, positive in operation and economical of manufacture.

Other objects and features of novelty of my invention will be specifically pointed out, or will become apparent when referring, for a better understanding of my invention, to the following description taken in conjunction with the accompanying drawings, wherein:

Fig. 1 is a view in side elevation of a honing device embodying features of my invention;

Fig. 2 is an end view of the structure illustrated in Fig. 1;

Fig. 3 is an enlarged broken sectional view of the structure illustrated in Fig. 1;

Fig. 4 is an enlarged sectional view of the tool and tool head of the device illustrated in Fig. 1;

Fig. 5 is an enlarged broken sectional view of the head and bearing support for the device;

Fig. 6 is a sectional view of the structure illustrated in Fig. 5, taken on the line 6—6 thereof;

Fig. 7 is a sectional view of the structure illustrated in Fig. 5, taken on the line 7—7 thereof; and

Fig. 8 is a view of structure similar to that illustrated in Fig. 4, showing a modified form thereof.

In the figures, I have illustrated a base 10, to which a shaft 11 is journaled in a bearing 12, having a plurality of recesses 13, 14, 15 and 16 therein. The left hand end of the shaft 11 is reduced in size and provided with a collar 17 over which a spring 18 extends, abutting against

the end of the bearing 12. The collar 17 is urged by the spring 18 against a ball-bearing 19 and a pulley 21, all of which is secured on the end of the shaft by a collar 22. A further reduced end 23 on the shaft 11 projects into a hollow shaft 24 between which a plurality of needle bearings 25 are disposed. The shaft 24 is also journaled in a bracket 26 which is part of the base 10. A second pulley 27 is mounted upon the hollow shaft 24, spaced from the bracket 26 by a thrust bearing 28. The pulley 27 is provided with a swash plate 29 which is provided with a recess for receiving a pin 31 projecting from the pulley 21. The relation and operation of the pulleys and shafts have been more fully described in the above-mentioned co-pending applications and are employed to provide the synchronized rotation and reciprocation to the shaft 11 which may be varied by changing the size of the pulleys and speed of the motor.

A motor 33 is mounted above the bearing 12 on a plate having a hinged connection 34 on one side, the opposite side being supported through a stud 35. The stud 35 may be adjusted to tilt the plate to regulate the tension on the belts 36 connecting the pulleys 37 of the motor to the pulley 21 and 27 of the device. The pulley 21 is free to operate on the shaft 24 against the thrust of the bearing 28, the shaft being secured to the bracket 26 by a suitable screw 40.

The opposite end of the shaft 11 carries an adjusting head 38 from which a tool 39 projects having a plurality of abrading elements 41 which are movable radially of the axis of the tool. The tool 39 comprises a body portion 42 having oppositely disposed slots 43 therein, in which the abrading elements 41 are disposed. Sloping surfaces 44 are provided in the slot mated with a tapered portion 45 of the abrading elements. Through the relative longitudinal movement of the tool body and abrading elements, the sloping surfaces will effect the radial movement of the elements axially of the tool body.

The body portion 42 has a shank 47 disposed centrally of a housing 48 disposed in the head 38. A pin 49 extends through the shank 47 and through slots 51 in the housing 48, the ends of the pin being received in an annular recess 52 provided in a cap threaded onto the housing 48. Through the adjustment of the cap 53 on the housing, the pin 49 is moved lengthwise thereof to adjust the shank 47 relative to the housing 48, lengthwise of the head 38. This adjustment regulates the degree of expansion capable of being applied to the abrading elements 41 through the adjustment of the actuating means therefor.

The abrading elements 41 have metal backing members 54 containing the sloping surfaces 45, which extend at 55 into the tool head 38 where they are provided with a flanged end 56. The flanged ends 56 are notched to receive a spring 57 which, in conjunction with a similar spring 58 at the outer ends of the members 54, urges the abrading elements 41 inwardly toward the axis of the tool. From the longitudinal movement of the flanges 56, the abrading elements are moved longitudinally of the body portion 42 of the tool and, in view of the sloping surfaces 44 and 45, move radially of the tool within a predetermined limit. Further expansion or contraction is obtained through the adjustment of the body portion 42 of the tool, as pointed out hereinabove.

For effecting the movement of the flanges 56

5 of the abrading elements 41, a cylinder 59 is provided in the housing 48 for each element, in which pistons 61 are mounted for movement longitudinally of the head. Piston rods 62 are connected to shoes 63, one of which engages each 10 of the flanges 56 of the abrading elements 41. Through the movement of the pistons 61 toward the tool end by the introduction of fluid in the upper end of the cylinders, the flanges 56 are moved therewith to permit the abrading elements to be contracted by the springs 57 and 58 toward the axis of the body 42. When fluid is introduced below the pistons the flanges are moved to the rear or driving portion of the device 15 to expand the abrading elements.

The shaft 11 journaled in the bearing housing 12 is provided with pairs of apertures 65 and 66 which communicate respectively with the fluid receiving pockets 14 and 15 provided in the housing. Fluid is delivered to the wells 14 and 15 through the conductors 69 and 71, illustrated in 20 Figs. 1 and 2. The wells 13 and 16 beyond the wells 14 and 15 are employed for receiving any of the fluid which might leak along the shaft 25 to be drained therefrom by the conductor 70 into a reservoir. The apertures 65 terminate in slots 73 which communicate with apertures 74 provided in the housing 48 and with apertures 75 which open into the bottom of the cylinders. The apertures 66 in the shaft 11 communicate at their 30 ends 76 to the top of the cylinder. In this manner like pressure is provided to the pistons in the cylinders and, since each piston is independently movable, independent adjustment of the 35 abrading element under like pressure is thereby provided. This is a very desirable and an important feature of the invention, and embodies a dry honing operation in which each of the abrading elements is movable different amounts when 40 urged by a like force. It is well known in the abrading art that the hardness of the abrading element varies and cannot be retained constant. For this reason, some of the abrading stones will deteriorate faster than others and result in the 45 binding of the tool or the necessity of providing compensating means to permit the tool to shift relative to the cylinder. In the present invention, the wearing of one stone faster than another is no obstacle in producing a perfect machine operation since any stone may be fed more 50 rapidly and moved a greater distance from the axis of the tool than another as the surface of the stone wears away. However, a like pressure is always maintained between the stone surfaces 55 and the cylinder wall so that a perfect honing operation results.

In operation the fluid is directed into the wall 5 to provide a pressure on the top side of the pistons 61 to force the abrading elements to the right as viewed in the Fig. 4, to thereby produce 10 the collapse of the abrading elements under the urge of the springs 57 and 58. When collapsed, a work piece may be removed from the abrading stones or a new work piece disposed relative to the stones in position to be machined. The motor 33 is operating to rotate the shaft 11 which is also reciprocated in view of the swash plate connection between the pulleys 21 and 27. Fluid pressure is introduced into the well 14 and vented 15 from the wall 16 to have the pistons 61 move to the left, as viewed in the figures, to draw the abrading stones to the left which, through the operation of the engaging surfaces 44 and 45, expands the abrading elements 41. The abrading elements will engage the surface of the work

piece to be machined under a like pressure until the operation is completed. Suitable stop elements may be employed to control the degree of expansion of the abrading elements. The adjustment of the collar 53 may be so regulated as to have the honing operation completed when the pistons 61 have reached the end of their stroke, that illustrated in Fig. 4.

In Fig. 8, I have shown a modified form of adjusting heads 38 wherein only a single pair of apertures, similar to the apertures 65, are utilized for expanding the abrading elements. Springs 77 produce the reverse movement of the pistons and the contraction of the abrading stones. It will be also noted in the figure that the cylinder 78 at the bottom of the figure is of shorter length than the upper cylinder 19. When a guide element of fiber, metal, cork or other substance is employed in the tool to expand therewith, the expansion of such material need not be as great as that for the abrading element since the guiding member does not wear away or at least does not wear away as rapidly as the abrading stone. For this reason a less degree of expansion will be required for the guiding member.

While I have described and illustrated but two embodiments of my invention, it will be apparent to those skilled in the art that various changes,

omissions, additions and substitutions may be made therein without departing from the spirit and scope of my invention as set forth in the accompanying claims.

5. What I claim is:

1. The combination in a tool, of a body, longitudinally shiftable, radially movable abrading elements in said body, means for moving said elements radially when shifted longitudinally, of independent pistons for actuating said elements longitudinally, and means for delivering a common fluid under pressure to said pistons.
10. 2. In an abrading tool, an abrading head comprising a plurality of longitudinally shiftable, radially movable abrading stones, independent actuating means for each stone, said means being shiftable longitudinally, and means for moving the actuating means to move said stones independently of each other, said means embodying 20 a source of fluid pressure.
15. 3. In an abrading head, a plurality of radially movable abrading stones, a body for supporting said stones, holders for said stones, pistons engaging said holders, a unit supply of fluid for 25 urging said pistons for independently actuating said stones radially, and means for adjusting the body relative to said pistons.

HARRY M. WHITTAKER.
